UNITED STATES PATENT OFFICE.

ALBERT ENNIS HENDERSON, OF TORONTO, ONTARIO, CANADA

AEROPLANE.

Application filed July 9, 1917. Serial No. 179,513.

The object of the invention is to provide an aeroplane with means for effecting bodily transverse movement thereof, in order to change its position upwardly, downwardly, and laterally in either direction, with a minimum speed of progressive movement to sustain the structure while travelling at a moderate rate of speed, to correct the tendency to side drift due to cross currents of air, and to secure rapidity of movement in maneuvering, while providing for the stable support of a pendent car which may be used offensively or defensively without interfering with the manipulation of the machine and under such conditions as to maximize the efficiency of the offensive and defensive equipment.

Further objects and advantages of the invention will appear hereinafter, it being understood that changes in form, size, proportions and details of construction may be resorted to within the scope of the appended claims, without departing from the spirit of the invention.

In the drawings—

Figure 1 is a side view of an aeroplane constructed in accordance with one embodiment of the invention:

Fig. 2 is a front view of the same;

Fig. 3 is a plan view;

Fig. 4 is a detail view partly in section of one form of universal suspension joint which may be used in the support of the pendent member;

Fig. 5 is a detail sectional view showing the gyroscopic stabilizer;

Fig. 6 is a detail view of the worm transmission gears for the auxiliary planes.

In the illustrated structure a conventional form of aeroplane proper is employed, the same embodying a frame 10, propellers 11 and guiding means including a rear rudder 12 and a front elevating and depressing plane 13, and also the lateral sustaining planes, upper and lower, shown at 14 and 15.

Arranged above the structure and suitably supported as by extensions 16 of the uprights of the main frame is a series of auxiliary sustaining planes 17, mounted upon horizontal axes 18, preferably consisting of rods extending transversely with two auxiliary planes on each rod and designed for simultaneous movement in either direction. As illustrated two sets of these transversely connected auxiliary planes are employed, said sets being located on either

side of the longitudinal center of the machine with an intervening space, and fore and aft these planes are distributed, so that corresponding numbers are arranged in front and in rear of the mid-length point or center of gravity of the structure to equalize the sustaining effect fore and aft and provide for a bodily transverse, that is upward or downward, movement of the entire structure. By adjusting these sustaining planes at an inclination upward toward their forward edges, to a greater or less degree it is possible with a comparatively slow progressive movement of the machine to maintain the same at any desired elevation.

In practice it is desirable to effect a simultaneous adjustment of all of these sustaining planes, and to this end the spindles 18 thereof may be provided with worm gears 19 meshing with worms 20 carried by an operating shaft 21 extending the full length of the series of planes and adapted to be turned in either direction by any suitable means, manual or motor.

Similarly, for effecting transverse bodily movement of the machine to one side or the other, or laterally, a longitudinal series of axially vertical planes 22 may be employed, mounted in a suitable superstructure 23 preferably over the longitudinal axis of the machine and having their spindles 24 provided with worm gears 25 meshing with worms 26 on an operating shaft 27, also extending longitudinally of the machine and adapted to be operated by any suitable means. The advantage in using worms and intermeshing gears for the adjustment of the planes resides in the fact that they are substantially locked and held at any desired adjustment, inclination, pitch or deflection, without auxiliary locking means.

The auxiliary, vertical or laterally deflecting planes 22, as described with reference to the vertically directing planes, are evenly distributed fore and aft of a mid-length point or the center of gravity of the machine so that a bodily displacement, of the machine in either direction may be secured with a comparatively slow progressive movement of the same, and moreover these axially vertical planes may be adjusted to a greater or less deflection from the vertical plane of the axial line of the machine, to compensate for side currents of air from any direction, to overcome a tend-

ency of the machine to drift, and it is obvious that the adjustment of said axially vertical planes may be effected independent 5 of that of the axially horizontal planes, so that a deflection of both from what may be termed their normal positions (parallel with the longitudinal axis of the machine) may be adopted to cause a bodily movement in a direction oblique to the longitudinal 10 axis or length of the machine.

Carried by the above described dirigible supporting member is a pendent member 28, preferably having its point of suspension from the supporting member at or below the 15 axis or the horizontal plane of the center of gravity of said supporting member and provided with stabilizing means such as a gyroscope 29, said suspension point being equipped with an universal joint 30, illustrated in detail in Figure 4, or any equivalent thereof. The mounting illustrated embodies a head 31 on the stem 32 of the pendent member, the under side of the head being convexed spherically for cooperation 25 with a spherically concaved seat 33 on the framework of the supporting member, with an interposed concavo-convex floating element 34 interposed between the faces of said head and seat with its surfaces in turn separated respectively from the head and seat by interposed anti-friction elements 35 and 36, each of which consists of a suitable cage in which is seated a plurality of anti-friction 30 balls. The opening in the seat through 35 which the stem extends should be made of a diameter sufficient to allow for any desired deflection of the supporting member from a horizontal position, while the registering opening in the floating member 34 should be of less diameter to provide for movement of the floating member in any direction due to the excessive inclination of the supporting member, while providing for a substantial bearing for or support of said pendent member. Stops 37 and 38 are provided on the 40 floating member for preventing displacement of the antifriction elements.

Also yielding guys 39 may be employed as shock absorbers, the same having springs 40 or equivalents thereof, and also to counteract any tendency of the pendent member to receive a rotatory movement. Moreover the pendent member may be constructed in the 45 form of an offensive or defensive cage or car, equipped with suitable armament such as torpedo discharging tubes 41, which, due to the stabilized support of the car, may be employed with accuracy in discharging missiles after the positioning of the supporting member with reference to the object of attack 50 has been effected.

Obviously, a peculiar advantage of the construction described, especially with reference to the means for controlling the supporting member, is that when the object of

attack is moving, the speed and direction of progress of the structure may be adjusted to correspond with that of said object or target, whereupon it is a matter simply of calculation, taking into consideration elevation 70 and wind drift, to discharge the missile so as to accomplish its purpose.

Having described the invention what I claim is:

1. An aeroplane having propelling and 75 guiding means, and supplemental planes, distributed fore and aft of mid-length of the machine, for imparting a bodily transverse drift thereto, a pendent, universally movable, car carried by the supporting member, and resilient shock absorbing means associated with said car for steadyng the same.

2. An aeroplane having propelling and 80 guiding means, a pendent stabilized car, auxiliary sustaining and drift planes distributed fore and aft of the point of support of said pendent member and above the horizontal plane thereof, and resilient shock absorbing means associated with said car for 85 steadyng the same.

3. An aeroplane having propelling and 90 guiding means, a pendent stabilized member and axially vertical laterally directing planes distributed fore and aft of the point 95 of support of the pendent member and in the vertical longitudinal plane thereof, and resilient shock absorbing means associated with said car for steadyng the same.

4. An aeroplane having propelling and 100 guiding means, a pendent universally supported stabilized member, auxiliary axially horizontal sustaining planes arranged in series upon either side of the vertical longitudinal plane of the point of support of said 105 pendent member, auxiliary axially vertical planes disposed in the vertical longitudinal plane or point of support of said pendent member, and means for independently adjusting said auxiliary planes.

5. An aeroplane comprising a fuselage having a horizontal rudder at one end, a vertical rudder at the other end, and a series of drift planes between said rudders swingable on vertical axes and a series of horizontal adjustable planes adjacent said drift planes, substantially as set forth.

6. An aeroplane comprising a fuselage, a main sustaining plane therefor, a horizontal rudder at one end of the fuselage, a vertical rudder at the other end, a series of drift planes between said rudders swingable on vertical axes, and a series of supplemental horizontal sustaining means at each side of said vertical drift planes adjustable about horizontal axes, substantially as set forth.

7. An aeroplane comprising a fuselage, a main sustaining plane adjacent the forward end thereof, spaced series of auxiliary sustaining planes at each side of the fuselage

and a series of drift planes between said series of auxiliary sustaining planes said drift planes being adjustable on vertical axes, substantially as set forth.

5. An aeroplane comprising a fuselage, a stabilized car on the fuselage, and a resilient shock-absorbing means extending forward and rearward from the lower portion of said car, said resilient means being 10 connected to the fuselage, substantially as set forth.

9. An aeroplane comprising a fuselage, a concave seat on the fuselage, a suspended car,

a stem on the car having a convex lower surface corresponding to said concave seat, a 15 plurality of anti-friction bearings between said surfaces, and a floating spacer interposed between said bearings said spacer having flanges for limiting its lateral movement and holding the anti-friction bearings 20 against excessive displacement, substantially as set forth.

This specification signed and witnessed this sixth day of July, A. D. 1917.

ALBERT ENNIS HENDERSON.
